UNITED STATES PATENT OFFICE.

LAZARUS WEIL, OF NEW YORK, N. Y.

DESIGN FOR A TRAY.

SPECIFICATION forming part of Design No. 27,602, dated August 31, 1897.

Application filed May 7, 1897. Serial No. 635,599. Term of patent 3¹/2 years.

To all whom it may concern:

Be it known that I, LAZARUS WEIL, of the city, county, and State of New York, have invented and produced a new and original Design for a Tray for Displaying Jewelry, of which the following is a specification.

My design consists in a tray or receptacle for displaying articles of jewelry.

In the drawings I have illustrated a tray embodying my design, in which—

Figure 1 is a plan view, and Fig. 2 is a section along the line 2 2 of Fig. 1.

Referring to the drawings in detail, A represents the base of the tray, which is triangular in outline, and B represents the side flanges, which project upwardly at right angles from the base, around the edge thereof. The flanges B are connected together so as to form angles at their junction, the sides of said flanges continuing in a straight line to the point of meeting one of the other flanges.

C designates the packing material in which the articles to be displayed are seated. In the present instance, the tray being designed for the purpose of displaying finger-rings, it is provided with the receptacle c.

The essential feature of the design is the triangular-shaped tray composed of a triangular base having vertically-extending sides or flanges along the edge of said base, said flanges meeting each other at the angles of the base.

What I claim as new is—

The design for a tray as herein shown and described.

In testimony whereof I have signed my name to this specification in the presence of two subscribing witnesses.

LAZARUS WEIL.

Witnesses:

FELIX H. LEVY,
G. B. TOWNSEND.
